(57) CLAIM

The ornamental design for an adapter for a video camera, as shown and described.

DESCRIPTION

FIG. 1 is a perspective view of an adapter for a video camera showing my new design;

FIG. 2 is a front elevational view thereof;

FIG. 3 is a right side elevational view thereof;

FIG. 4 is a top plan view thereof; and,

FIG. 5 is an enlarged cross sectional view thereof along the lines 5-5 and 5'-5' of FIG. 2.

The broken lines in the drawings are included for the purpose of illustrating environmental subject matter and form no part of the claimed design.
